UNITED STATES PATENT OFFICE

132,100

DESIGN FOR A COMBINED PLATE AND SAUCER

Harold N. Ipsen, Rockford, Ill.

Application December 12, 1941, Serial No. 104,600

Term of patent 7 years

To all whom it may concern:

Be it known that I, Harold N. Ipsen, a citizen of the United States, residing at Rockford, in the county of Winnebago and State of Illinois, have invented a new, original, and ornamental Design for a Combined Plate and Saucer, of which the following is a specification, reference being had to the accompanying drawing, forming part thereof.

In the drawing:

Fig. 1 is a top plan view of the combined plate and saucer, showing my design;

Fig. 2 is a front elevational view thereof.

Fig. 3 is a sectional view, taken along line 3—3 of Fig. 1 and in the direction of the arrows, and

Fig. 4 is a side elevational view thereof.

I claim:

The ornamental design for a combined plate and saucer, substantially as shown.

HAROLD N. IPSEN.
